SKI BINDING

John M. Piane, Hanover, N. H.

Application May 13, 1947, Serial No. 747,621

4 Claims. (Cl. 280—11.35)

1

This invention relates to a ski-binding for attaching a ski to the foot of the wearer, and particularly to a simple and inexpensive binding suitable for use by children and youths with all types of footwear.

Hitherto there have been no suitable and practical ski bindings available for children's use, except the relatively expensive types of bindings used by adults and expert skiers, which also require expensive ski boots for their successful use. In consequence, children have had to use the old-fashioned leather strap type of binding, which is not readily or easily attachable or detachable, and which does not permit the children to get into and out of them easily without aid, and which does not hold the foot properly to the ski to promote proper skiing technique. Accordingly, I have sought to devise a ski-binding which should have all the advantages of the expensive cable type of binding, but which would be relatively inexpensive, and would not require an expensive and specially-made type of ski boot for its successful use.

Briefly, my invention includes a round cable type of harness for attaching the foot to the ski, but having a cable made of relatively non-resilient material, such as plastic or rubber, or cord, such as nylon, cotton or the like, and covered with plastic or rubber, and providing limited or restricted stretchability, and which is round at the toe and sides, and having a flat strip of stretchable rubber forming the sides and rear at the heel portion, and which is molded or otherwise attached to the round section, a releasable clamp for tightening the cable around the foot and so attaching the foot to the ski, a metal foot plate secured to the ski, with a rigid metal toe plate, cable side guides formed thereon, and a flexible and adjustable toe strap. With such a binding, any ordinary boot can be used, with rubbers, or rubber overshoes if desired (as well as a ski-boot) and the binding will fit the shoe, and will hold the shoe resiliently attached to the ski at all times. The self-centering toe plate and cable permit the skis to be interchangeable left for right, and the fact that there is no rigid toe side irons reduces the possibility of twisting the ankles, as the foot is enabled to pivot at the toe and the heel is enabled to move from side to side under tension of the cable, and will be pulled back into position by the resilient portion of the cable.

Before explaining in detail the present invention it is to be understood that the invention is not limited in its application to the details of

2

construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Other advantages and objects of my invention will appear in the following specification and accompanying drawings, in which:

Fig. 1 is a plan view of my ski binding;

Fig. 2 is a side elevation thereof;

Fig. 3 is a vertical section on lines 3—3 of Fig. 1; and

Fig. 4 is a vertical section on lines 4—4 of Fig. 1.

In the drawings, 10 represents the ski and securely fastened thereto in proper position is a foot plate 12, preferably of metal, and of one piece construction. Mounted directly on the ski as by means of screws 11 is the flat rear section 13, and which has sidewise extensions bent to curve slightly around the cable 20 to form guides 14 for the cable. The guides 14 thus provide a snap fit to hold the cable in place alongside of the ski, but allow it to run freely through the guide. Extending forwardly from the rear section 13 of the foot plate, is the sole section 15 which is offset or elevated slightly above the plane of the section 13 to allow the toe strap 25 to be passed under the sole section 15 and between it and the ski 10. A second set of screws 11 pass through the sole section 15 and the bottom of the toe strap 25 into the ski 10. The forward end of the foot plate 12 is slotted at its middle about one inch inwardly and the two pieces thus formed are bent upwardly and slightly rearwardly to form a toe plate 16. The plates 16 also incline slightly from the front center toward the sides so that the toe plate will automatically center the boot in the ski binding.

The toe strap 25 is a strip of leather or other suitable flexible material passed under the sole portion 15 of the foot plate 12 and secured thereto by screws 11. The free ends of the toe strap 25 are suitably perforated as at 27 and tied together as by a lacing 26. An auxiliary row of holes 27a is provided to make the toe strap adjustable to fit varying sizes of shoes.

The cable 20 is made of rubber or plastic round at the front and sides 21, or is a rubber-coated or plastic-coated cord and having an inner core 55 of a suitable fibre such as nylon, cotton, fabric

or the like, and which round section of the cable is relatively non-stretchable, or of limited stretchability. Molded, or otherwise suitably attached, to the round section of the cable, is a flat strip of resilient rubber 22 designed to pass around the rear of the shoe 30. The flat section 22 should be sufficiently resilient to permit the heel of the shoe to rise at least two inches above the plane of the ski. Normally in cable-type bindings, the cable binds the specially-constructed ski-boot at the heel, which is grooved, to retain the cable, but in my construction, designed to be used with any type of shoe, or overshoe, the cable passes around the shoe above the heel, as shown in Fig. 2. The inside rear portion of the section 22 of the cable 20 is preferably cross-hatched or otherwise treated at the section 23 to reduce slippage of the cable against the back of the skier's shoe.

The cable 20 is adjustable to hold the skier's shoe tightly in the ski binding by means of the adjustable clamp 35 of conventional type, having a flat base portion 36 which is attached to the ski as by means of screws 31. The base 36 has two sides 38 extending upwardly and at the higher portion thereof at the rear as at 39, the lever 40 is pivotally attached thereto as its bottom end. Lever 40 carries on its forward end a flanged stop 41 and intermediate its ends as at 42 a ladder 44 is pivotally attached thereto by means of its two side arms 43. At its rear end ladder 44 has formed therein a series of hooks 45 to receive the cable 20. The hooks 45 are bent forward on approximately the same radius as that of the cable, but the tabs at their extremities are bent downward and then up making it possible to snap the cable into place and hold it, at the same time allowing the cable to run free of the hook. The clamp is operated in the usual manner by raising the lever 40 to allow the cable 20 to be inserted under the appropriate hook 45 and the clamp is tightened by pushing the lever 40 forwardly and downwardly about its pivot which carries with it by a forward pull the ladder 44. Thus tightened, the cable 20 holds the foot of the wearer forward snugly in the binding and against the toe plates 16.

It will thus be seen that I have provided a child's ski binding suitable for use with ski boots, overshoes, rubbers of any type, which is simple and economical, and which will hold a child's feet securely to the skis and without danger of twisted ankles and yet permit the children to get in and out of the binding without aid.

I claim:

1. In a ski binding, a metal foot plate secured to the ski and having a pointed toe plate formed at the front thereof and cable guides at the rear sides thereof, a toe strap of flexible material se-

cured to the ski by said toe plate, a relatively non-resilient cable of flexible material having a resilient flat section extending around the rear of the wearer's foot, and a releaseable clamp secured to said ski for pulling said cable tight around the wearer's foot.

2. In a ski binding, a metal foot plate secured to the ski and having a pointed toe plate formed at the front thereof and cable guides at the rear sides thereof, a toe strap of flexible material secured to the ski by said toe plate, a relatively non-resilient rubber cable having a resilient flat section extending around the rear of the wearer's foot and a releaseable clamp secured to said ski for pulling said cable tight around the wearer's foot.

3. In a ski binding, a metal foot plate of one piece construction secured to the ski and having a pointed toe plate formed at the front thereof and cable guides at the rear sides thereof, a toe strap of flexible material secured to the ski beneath a portion of said foot plate, a relatively non-resilient rubber-coated cable having a resilient flat section extending around the rear of the wearer's foot, and a releaseable clamp secured to said ski for pulling said cable tight around the wearer's foot.

4. In a ski binding, a metal foot plate of one piece construction secured to the ski and having a toe plate formed at the front thereof and cable guides at the rear sides thereof, said toe plate being slotted at the middle and sloped rearwardly from the middle toward the sides of the foot plate, a toe strap of flexible material secured to the ski beneath a portion of said foot plate, a relatively non-resilient cable of rubber-coated flexible material having a resilient flat section extending around the rear of the wearer's foot, and a releaseable clamp secured to said ski for pulling said cable tight around the wearer's foot.
